DESIGN FOR A CLOCK

Leo Y. Booharin, San Francisco, Calif., assignor
of one-fourth to William J. Delaney, one-fourth
to Perry W. Wood, and one-fourth to Charles
F. Attinger

Application June 17, 1939, Serial No. 85,536

Term of patent 14 years

To all whom it may concern:

Be it known that I, Leo Y. Booharin, a citizen
of the United States, residing at the city and
county of San Francisco and State of California,
have invented a new, original, and ornamental
Design for a Clock, of which the following is a
specification, reference being had to the accom-
panying drawing, forming part thereof.

Fig. 1 is a front elevational view of the clock,
showing my new design.

Fig. 2 is a side elevational view of the clock
shown in Fig. 1.

I claim:

The ornamental design for a clock, as shown.

LEO Y. BOOHARIN.
